UNITED STATES PATENT OFFICE.

JAMES R. DUNN, OF BALTIMORE, MARYLAND.

BOTTLE-CLOSURE.

1,083,389.

Specification of Letters Patent.

Patented Jan. 6, 1914.

Application filed September 13, 1912. Serial No. 720,230.

To all whom it may concern:

Be it known that I, JAMES R. DUNN, a citizen of the United States, residing at Baltimore, in the State of Maryland, have 5 invented new and useful Improvements in Bottle-Closures, of which the following is a specification.

This invention relates to bottles and particularly to means adapted to be used in 10 bottles of ordinary form to make them non-refillable unless noticeably damaged.

It is an important object to provide a self-contained device adapted to be engaged in a bottle neck by the usual corking apparatus in conjunction with the driving of a cork thereinto, and which will include both 15 the means to prevent ingress of fluid and protective means to prevent the introduction of instruments to interfere with the operation of the device.

The device is in the nature of a valve and utilizes the principle of the pendant, weight-controlled spherical valve, but in addition provides a guard construction so arranged 25 as to coöperate with the valve for the improvement of its operation.

It is also a purpose to enable the manufacture of the device compactly, cheaply and by very simple operations well adapted to 30 be carried out by machinery.

It is one aim to give a maximum capacity for the flow of liquid and air through re-curved passages in a device to be fitted in a bottle neck, and also to so shape these 35 passages that they may be readily stamped or molded.

It is also a further purpose to provide efficient means for guarding the contents of a bottle equipped therewith against contact 40 with substances used in the securement of the device in place.

Additional objects and advantages will be apparent, some of them evident from the following specification and from the drawings, in which—

Figure 1 is a sectional view of a portion of a bottle equipped with my invention, Fig. 2 is a similar view showing the device inverted, Fig. 3 is a perspective view of one 50 section of the device detached, Fig. 4 is a cross section on the line 4—4 of Fig. 1, Fig. 5 is a longitudinal sectional view of a modification of the device.

There is illustrated a bottle 10 of a familiar form, the neck 11 of which is provided with a shoulder 12 near its base on the

inside, forming a seat for the support of my device. However, my invention is applicable to use with the ordinary bottle in which the neck is usually slightly swelled outward at its intermediate part, as will 60 become apparent.

The device in the neck comprises a casing 13 in two sections, joined on a diametrical plane. The casing is circular in cross section and at the lower end is provided with a large recess 14 semi-spherical in shape, whereby the lower or inner end of the casing is tapered to a very thin edge. It will be observed that the bottle neck slopes slightly inwardly toward the shoulder 12, and the 70 tapered annular apron portion 15 of which the thin edge forms a termination formed on the lower part of the casing engages against this sloping portion yields, and accommodates itself to the form of the neck 75 and forms a liquid-tight fit. The casing is preferably made of a readily malleable metal so that the attenuated lower portion may yield slightly to the side of the bottle neck as it is forced thereinto and the snug 80 fit be assured without liability of breaking the bottle.

The metal that has been used in practice and found to operate most satisfactorily is ordinarily lead, but any other material having similar properties of softness may of course be used.

A concentric port 16 is formed in the inner end of the casing, opening into a valve chamber 17, a spherical seat 18 being formed 90 on the inner side of the port adapted to properly accommodate the valve 19 engaged in the chamber and having the attenuated stem 20 projected outwardly through the port and adapted to play laterally therein, 95 being of a length to lie within the plane of the base when the valve is seated. The outer end of the stem is weighted as at 21. The sides of the port 16 are preferably in the form of a frustum of a cone apically concentric with the seat 18. The casing is provided with a peripheral recess or channel 22 the breadth of which extends over more than half the length of the casing, being in the neighborhood of one inch broad, in practice 105 in which there is secured a filling of cork or other suitable cushion and friction material extending a proper distance from the outer periphery of the casing to hold securely upon the bottle. The casing is provided with a passage 23 leading in from

the outer end of the device, to a cup-like portion 24 surrounding the passage, the passage stopping short of the inner or bottom part of the cup, on each side blind passages 5 25 lead from the valve chamber 17, being suitably proportioned and extended beyond the edges of the cup to form communication therearound from the port to the passage 23, the sides of the cup being spaced centrally 10 therein. The lower side of the cup is so formed and disposed as to coöperate with the valve to check it at the outer limit of its movement, and to engage the valve in such a way when the bottle is inclined as 15 to form a fulcrum against which one side of the valve will bear while the other, under the effect of gravity on the weight 21 and also on the valve under a certain amount of inclination will be forced toward the seat 20 18 as shown in Fig. 2 when there is no liquid in the bottle. The dotted line $a-a$ in that figure is drawn from the point of contact of the valve with the cup approximately through the center of gravity of 25 the valve and weight and stem and by placing the figure in such position that this line is vertical, it will be understood how much the bottle must be tipped before the valve becomes unseated. In such position it is 30 not practicable to introduce a liquid. It will be seen, however, that the presence of even a very small amount of liquid in the bottle will be sufficient to unseat the valve when the bottle is sufficiently inclined. 35 The casing sections are adapted to be formed by molding or by stamping, in manufacture, and, as shown in Fig. 4, each may be struck in one operation by the use of one-piece dies, the passages being formed in 40 somewhat flattened form and in parallel relation so that the male die may be readily withdrawn.

It will be observed that the outer bottom surface of the cup portion is flattened to 45 correspond to the top of the valve, and so spaced from the seat 18 that there will be provided a proper clearance for the passage of fluid from the bottle, and the ingress or air. As indicated by the arrows, the fluid 50 may flow outwardly at the lower side while air gains access at the upper side. In the upper side of the casing a bowl-like recess 55 is formed which will be useful in the emplacement of a cork when the device is applied to a bottle.

In use, a bottle being constructed as shown is filled in the ordinary way, without my invention in place, and is then positioned beneath the stopper driving machine. One of 60 my casings is then presented in the mouth of the bottle and the stopper driver operated. The bowl-like portion 26 will guide the cork into a central position on the casing, and will be fitted tightly into the bowl-like recess closing the outer end of the pas-

sage 23 by pressing thereagainst, and thus keeping all liquid inwardly of the casing. The stopper driving machine forces the casing into place at the same time that the stopper is engaged tightly in the mouth of 70 the bottle. Before being driven, a suitable cement may be applied to the cork 22' so that the device will be securely held against withdrawal. If the device be used in a bottle without the shoulder 11, it should be 75 slightly restricted toward the lower end of the neck and the apron 15 will then be compressed and tightly fitted therein.

The cork packing 22' will serve to hold the sections in proper operative relation, and to 80 maintain them in proper registry at all times suitable interlocking lugs and recesses may be formed on the abutting surfaces of the sections.

The walls of the passage 23 may be of 85 such thickness as necessary to guard against the insertion of an implement for the unseating of the valve, and the bottom of the cup may also be made of such thickness as not to be easily punctured, but the sides of 90 the cup may be paper-thin, and a maximum space left in the passages. The valve and weight thereon may be formed of the same metal as the casing if desired, or if preferable may be formed of glass. 95

In Fig. 5, there is shown a modification of the device, in which a cup-shaped screen 27 is engaged in the chamber above the valve, serving as an additional precaution against the access of an instrument or other 100 objects for the purpose of unseating the valve. This cup screen 27 is inserted at the same time as the valve, into one half of the device and the other half then engaged thereover. 105

What is claimed is:

1. A device of the class described comprising a casing adapted to be engaged in the neck of a bottle and having a valve chamber therein, a port opening from the valve chamber at the inner end of the casing, a semi-spherical seat at the inner end of the port, a semi-spherical valve seated thereon, having a reduced stem projecting through the port and provided with a weight at its 110 outer end, the stem being adapted for loose lateral movement across the port, blind passages formed in the casing, opening on and extending from the valve chamber longitudinally outward in the casing, a cup member U-shaped in longitudinal section formed integrally with the casing and joined thereto at opposite sides, the sides of the cup 115 extending outwardly into the blind passages, stopping short of the outer ends of the passages and being spaced centrally thereof, the bottom of the cup member forming the outer side of the valve chamber and being disposed to check the valve at the outer limit of its movement, the base of the 120 125 130

cup having lateral fulcrum portions arranged and adapted to engage the outer side of the valve at the outer limits of its lateral sliding movement also, whereby the valve 5 will be held to its seat in the manner described, a passage being formed through the outer end of the casing and opening into the cup adjacent its inner end.

2. In a bottle closure, a casing of yielding metal having passages therethrough and a gravity seated valve inclosed therein to close communication therethrough except when inverted, an annular peripheral apron formed on the lower end of the casing 10 tapered to a thin edge, and a bottle neck tapering inwardly, whereby the metal of the casing apron when forced into the neck will be compressed and conformed to the shape of the neck to form a liquid-tight seal.

3. A bottle closure comprising in combination, a neck having an inner inwardly 15

tapered portion, a casing of yielding metal in the neck having passages therethrough, a check valve in the casing to close the neck against ingress of liquids, said casing having a circumferential recess therein approximating in length the usual cork stopper for necks of similar size to that above named, cork-like material in said recess, projecting therefrom to engage the sides of the bottle 25 neck against extraction of the closure, an annular apron formed integrally on the lower end of the casing tapered to a thin edge, and engaged snugly against the convergent surfaces of the neck.

In testimony whereof I have hereunto set my hand in presence of two subscribing witnesses.

JAMES R. DUNN.
